ELECTROSURGICAL UNIT

Ulises M. Lopez, West Hempstead, Martin I. Septimus and Henry A. Holzwarth, New York, and John D. Wark, Freeport, N.Y., assignors to Cavitron Corporation, Long Island City, N.Y.

Filed Dec. 7, 1970, Ser. No. 26,318

Term of patent 14 years

Int. Cl. D24—02

U.S. Cl. D83—1

FIG. 1

FIG. 2

FIG. 3

FIG. 4

FIG. 1 is a front elevation view of an electrosurgical unit showing our new design;

FIG. 2 is a rear elevation view of the electrosurgical unit;

FIG. 3 is a top plan view of the electrosurgical unit; and

FIG. 4 is a left side view of the electrosurgical unit.

The undisclosed right side of the electrosurgical unit is substantially the same in appearance as the left side.

We claim:

The ornamental design for an electrosurgical unit, substantially as shown and described.
